UNITED STATES PATENT OFFICE.

LULU TEETER SMITH, OF WATERLOO, IOWA.

CHILD'S MUSIC RACK.

Application filed December 1, 1922. Serial No. 604,352.

To all whom it may concern:

Be it known that I, LULU TEETER SMITH, a citizen of the United States of America, and a resident of Waterloo, Blackhawk County, Iowa, have invented certain new and useful Improvements in Children's Music Racks, of which the following is a specification.

My invention relates to improvements in music-racks, and the object of my improvement is to supply particularly for use by children a device of this nature, simple in construction, inexpensive, and adapted to be releasably mounted on a shelf or projection, such as the book or music-holding shelf of a piano, from which the device may depend to support a book or sheet-music at a lower level where it will be located more conveniently for a child to use.

This object has been accomplished by the means which are hereinafter described and claimed, and which are illustrated in the accompanying drawings, in which Fig. 1 is a view of this device as mounted upon a ledge or shelf of a piano. Fig. 2 is a front elevation on a larger scale, of the device, demounted. Fig. 3 is a side elevation of the device mounted on a piano shelf and supporting a book or piece of sheet music.

My improved child's music rack is constructed from a single piece of elastic rod which is medially bent or shaped into an elongated approximately horizontal loop of which the opposite longitudinal parts or reaches 1 and 2 are slightly bowed upwardly. The end parts 3 are bent convergently, angularly, and obliquely upwardly to the rear then bent forwardly, side by side at 4, then recurved at 5 to provide the rearwardly directed parts 6, the parts 6 being bent divergently and having their terminations 7 then bent toward each other in alinement to supply the closed triangular loop which is substantially parallel with the parts 4 underneath, and thus providing a resilient clip which may be releasably mounted on the shelf 10 of the hinged front panel 11 of the upper part of the piano 12. This positions the loop 1—2 slightly above the rear part of the keyboard 13, as shown in Fig. 1, and

nevertheless not interfering with the proper use of the keys.

The device thus far described is complete and operative for the purpose of being mounted removably upon the usual music shelf or other projection of a piano for supporting upon its loop 1—2 a music-book or sheet 14 where the latter will be located horizontally opposite the eyes of a child for close and convenient reading without discomfort.

I have shown, in combination with the device, a soft and flexible lining 8, which may be made of any suitable material, such as felt, for lining the inner surfaces of the clip members 4—6 to prevent abrasion or injury to the varnish or finish of the supporting shelf 10. The rectangular strip 8 may have its upper end folded over tubularly at 9 about the alined terminal parts 7, secured by stitching or otherwise, to depend therefrom as shown in Fig. 2. As shown in Fig. 3, when said clip is pushed over the shelf 10, the strip 8 is drawn between the members of the clip to enfold the shelf between 75 said members. The abutted ends of the terminals 7 may be soldered or welded together if desired.

It is to be understood that slight changes in the described structures may be effected without departing from this invention and the scope of its protection.

Attention is also called to the peculiar upwardly bowed shape of the reaches 1 and 2 of the forward loop, said reaches thus preventing escape of the book or sheet 14, but the bowing of these parts is not of enough extent to prevent free turning of the leaves.

Having described my invention, what I claim as new and desire to secure by Letters Patent, is:

1. A child's music rack, consisting of a single elastic rod medially bent into a substantially horizontal elongated loop the forward longitudinal reach of which is slightly bowed upwardly to serve as a front stop for music sheets, end parts of the rod being angularly projected from said loop in one direction slopingly upwardly with their terminals recurved upon themselves with ex- 100

tremities in alignment to provide resilient clips.

2. A child's music rack, comprising an elastic rod medially bent into an elongated horizontal loop having angularly directed upwardly sloped end members, said members shaped into a U-shaped resilient clip whose upper part is formed into a closed

loop with a transverse terminal reach, and a flexible strip pad mounted at one end 10 dependingly upon said terminal reach to line the inside of the U-shaped clip.

Signed at Waterloo, Iowa, this 30th day of October, 1922.

LULU TEETER SMITH.
